UNITED STATES PATENT OFFICE.

GIUSEPPE VIRZI, OF NEW YORK, N. Y.

SOUND-PRODUCING INSTRUMENT.

1,408,150.

Specification of Letters Patent. Patented Feb. 28, 1922.

Application filed October 21, 1920. Serial No. 418,415.

To all whom it may concern:

Be it known that I, GIUSEPPE VIRZI, a subject of the King of Italy, but having declared my intention of becoming a citizen of the United States, and residing at 341 East 124th Street, New York city, in the county of New York and State of New York, have invented certain new and useful Improvements in Sound-Producing Instruments, of which the following is a specification.

This invention relates to sound producing instruments and has particular reference to means for increasing the force or resonance of the tones produced thereby.

The spirit of this invention may be carried out in many ways, but I have illustrated in the accompanying drawings and whereon similar reference characters are applied to corresponding parts of different views, the invention applied to talking machine reproducers and of which drawings—

Fig. 1 is a vertical sectional view of a reproducer head of a talking machine showing my invention.

Fig. 2 is a front elevation of the same.

I illustrate a talking machine sound box 17 having secured within its rim 18 a vibratory body or diaphragm 19 of any suitable construction, the periphery of the diaphragm being gripped between resilient gaskets 20.

At 21 I indicate a stylus bar connected in any suitable manner to the lower portion 35 of the sound box and adapted for oscillation toward and from the plane of the diaphragm 19 as is well understood. Differing from the usual stylus bar, however, this one is provided with a plurality of fingers 22 and 23. The finger 23 is shown as projecting through 40 the center of the diaphragm 19, and it may be secured to the diaphragm 19 by any suitable means such as wax or glue.

Associated with the main diaphragm 19 are one or more auxiliary sound producing means shown as diaphragms 24 and 25 spaced from one another and from the main diaphragm and on either the inside or the outside of the box. As shown the auxiliary 50 diaphragms or sound transmitters are arranged one on the inside of the box and the other on the outside. The edges or periph-

eries of the auxiliary diaphragms are free or spaced from all other structure.

The finger 23 extends through all of the 55 diaphragms and in connection with a washer 26 constitutes the sole support for the innermost diaphragm 24. The fingers 22 are attached to the outermost diaphragm 25 and constitute the means for supporting 60 it, in connection with the center finger 23. The diaphragms are all so constructed or designed as to harmonize with one another so that the tone vibrations imparted thereto or transmitted therethrough will either be 65 in unison or in harmony, in order to produce the most satisfactory and pleasing rendition of the tone. Furthermore, the several auxiliary diaphragms must be so designed as to take account of the different means for sup- 70 porting them.

I claim:

1. In a sound producing instrument, the combination of a main vibratory member, a movable member connected to the vibratory member to cause the vibration thereof, a second vibratory member adjacent to the main vibratory member, the connecting means between the main member and the movable member extending through the second mentioned vibratory member, and means auxiliary to said connecting means to support the second vibratory member.

2. In a sound producing instrument, the combination of a main diaphragm, movable means to cause the vibration thereof, an auxiliary diaphragm, and other sound producing means adjacent to but spaced from the main diaphragm, said movable means including a member connected to both diaphragms and also to said other sound amplifying means.

3. A device as set forth in claim 2 in which the connecting means between the movable member and the diaphragms consists of a finger extending through the centers of the diaphragms.

4. A device as set forth in claim 2 in which the auxiliary diaphragm is located on the opposite side of the main diaphragm from the movable member.

5. In a sound producing instrument, the combination of a sound box including a main diaphragm, a movable member on the

outside of the diaphragm but connected therewith to cause vibration thereof, an auxiliary diaphragm within the sound box, and a member extending from the movable member 5 aforesaid to support the auxiliary diaphragm.

6. A device as set forth in claim 5 in which a second auxiliary diaphragm is pro-

vided and located on the other side of the main diaphragm from the first mentioned 10 auxiliary diaphragm, and means are provided to co-operate with the movable member and supporting means mentioned to cause all three diaphragms to vibrate at the same time, substantially as set forth.

GIUSEPPE VIRZI.
